(57) **CLAIM**

The ornamental design for a headgear article having recessed portions, as shown and described.

DESCRIPTION

FIG. 1 is a perspective view of a headgear article having recessed portions showing our new design;

FIG. 2 is a front elevational view thereof;

FIG. 3 is a left side elevational view thereof, the right side view being a mirror image thereof;

FIG. 4 is a rear elevational view thereof;

FIG. 5 is a top plan view thereof; and,

FIG. 6 is a bottom plan view thereof.

The broken lines form no part of the claimed design.
